[57] CLAIM

The ornamental design for an inkfilm cartridge, as shown and described.

DESCRIPTION

FIG. 1 is a right front perspective view of an inkfilm cartridge showing my new design;
FIG. 2 is a front elevational view;
FIG. 3 is a rear elevational view;
FIG. 4 is a top plan view;
FIG. 5 is a bottom plan view;
FIG. 6 is a right side elevational view; and
FIG. 7 is a left side elevational view thereof;
FIG. 8 is a right front perspective view of a second embodiment showing my new design;
FIG. 9 is a front elevational view;
FIG. 10 is a rear elevational view;
FIG. 11 is a top plan view;
FIG. 12 is a bottom plan view;
FIG. 13 is a right side elevational view; and,
FIG. 14 is a left side elevational view thereof.
